UNITED STATES PATENT OFFICE.

JACKSON J. KENNEDY, OF CLEVELAND, TENNESSEE.

CAR-COUPLING.

SPECIFICATION forming part of Letters Patent No. 356,320, dated January 18, 1887.

Application filed November 30, 1886. Serial No. 220,308. (No model.)

To all whom it may concern:

Be it known that I, JACKSON J. KENNEDY, of Cleveland, in the county of Bradley and State of Tennessee, have invented a new and useful Improvement in Car-Couplings, of which the following is a specification.

Figure 1 is a plan view of the coupling. Fig. 2 is a vertical cross-section through the line $x-x$, looking in the direction of the arrow.

Fig. 3 is a section of the draw-bar where it passes through the bearings in the frame-work of the car. Fig. 4 is a cross-section through line $y-y$ of Figs. 1 and 5, and Fig. 5 is a longitudinal section of the draw-bar through its slot.

My invention relates to certain improvements upon the form of car-coupling patented by me August 8, 1882, No. 262,433, and May 25, 1886, No. 342,608; and it consists, mainly, in the improved construction of the draw-bar, its locking-key, and its bearings, as will be hereinafter fully described, and pointed out in the claims.

In the drawings, A represents the draw-bar, which, as described in my previous patents, is a rotary adjustable draw-bar, oscillating about the longitudinal axis, and having at its front end an offsetting goose-neck, a, head b, and inclined beak c, which latter occupies a diagonal position between the vertical and horizontal, and is beveled on its face, so that when the two beaks of the opposite draw-bars come together the inclined faces of the beaks cause the draw-bars to turn axially until the beaks pass, and they then are rotated by their own gravity back again into the normal diagonal position and hook or lock into each other, so as to couple the cars, as in Figs. 1 and 2.

One feature of improvement consists in making the head b of each draw-bar large and forming it with a link-throat, d, with closed sides, and a pin-hole and pin, e, which adapt it to couple with the draw-bars of ordinary cars, the offset in the goose-neck permitting the draw-head to be adjusted either above the central line or below the central line by being turned over, and thus adapting this head to couple with cars of different heights.

Where the draw-bar passes through the

bearing in the frame-work D of the car, said bearing is recessed, so that only certain points of the inner face of the bearing touch the draw-bar, as shown at $ffff$, Fig. 3, the intervening spaces being out of contact with the draw-bar and forming oil-cavities. This reduces friction and renders the rotary action of the draw-bar easier and free from cramping strains.

To render the draw-bar yielding, its rear end is reduced in diameter and a shoulder left at r, against which a ring or disk, u, bears, and behind which a spiral spring, D, is disposed and wound around the shaft. The rear end of this spring bears against a ring or disk, C, and this in turn bears against a shoulder-key, B, passing through a slot in the draw-bar. This arrangement, in connection with cross-bars E E, makes the draw-bar elastic both in pulling and backing. To hold the key B in place, it is formed on one side with a shoulder, s, Fig. 4, which prevents it from passing through the slot, and on its edge it has a shoulder, t, Fig. 5, which is overlapped by the ring C, and by it is prevented from coming out. To remove key B, ring C is pressed back against the spring D till shoulder t is cleared, and the key can be then withdrawn.

Having thus described my invention, what I claim as new is—

1. The combination, with the slotted draw-bar, the spiral spring D, and ring C, of the shoulder-key B, having a shoulder, s, on its side and another shoulder, t, on its edge, arranged to be overlapped and locked by the said ring, substantially as described.

2. An axially oscillating draw-bar having a goose-neck, a, head b, and beak c, offsetting from the axial line, with a link-throat, d, and pin hole formed in the head, substantially as and for the purpose described.

3. The combination, with an axially oscillating draw-bar, of a bearing for the same, having a recessed inner periphery to reduce friction, substantially as shown and described.

JACKSON J. KENNEDY.
